UNITED STATES PATENT OFFICE.

VICTOR BEAUREGARD, OF BOSTON, MASSACHUSETTS.

DESIGN FOR A FINGER-NAIL TOOL.

58,210.

Specification for Design.

Patented June 28, 1921.

Application filed November 13, 1920. Serial No. 423,993. Term of patent 14 years.

To all whom it may concern:

Be it known that I, VICTOR BEAUREGARD, a citizen of the United States, residing at Boston, in the county of Suffolk and State of Massachusetts, have invented a new, original, and ornamental Design for a Finger-Nail Tool, of which the following is a specification.

Figure 1 is a view of one side of a finger nail tool showing my new design.

Fig. 2 is an edge view of the same.

Fig. 3 is a view showing the opposite side.

Fig. 4 is a transverse section, taken midway between the ends of the tool.

The design is characterized by an oblong body and longitudinal parallel bosses formed thereon, each boss being convex at one side, and concave at the opposite side, the concave sides being diversified by transverse parallel grooves.

I claim:

The ornamental design for a finger-nail tool, as shown.

In testimony whereof I have affixed my signature.

VICTOR BEAUREGARD.
